[57] ABSTRACT

An induction heating apparatus for heating in depth the surface of the rolls of a rolling mill including an inductor fed by an alternating current of low or medium frequency and a device permitting the rolls to rotate around their axes. The inductor comprises two end frames and two lateral conductors connecting the two end frames so as to form an inductor having two longitudinal symmetry planes which are perpendicular with respect to each other. There is also provided a device for regulating the device permitting to rotate the rolls around their axes, such regulating device being arranged so as to permit the axes of the rolls to coincide with the intersection line of the two longitudinal symmetry planes.

FIG. 2

INDUCTION HEATING APPARATUS

This invention relates to an induction heating apparatus for heating in depth the surface of the rolls of a rolling mill, and more particularly of rolls which are heavy and voluminous.

Induction heating apparatus for the rolls of rolling mills are known, such as, for example, an apparatus in which a roll is suspended to a rotating hook or any device permitting to rotate the roll around its axis and in which a circular inductor is displaced longitudinally along the roll while the roll is rotating. The inductor of such a known device is fed by an alternating current of low or medium frequency. Such known apparatus, which is relatively simple, is suitable for the rolls of rolling mills which do not present any major handling problems.

The object of the present invention is to provide an induction heating apparatus used for the surface heating of the rolls of a rolling mill which are particularly voluminous and heavy, for example for the rolls the diameter of which exceeds 1.5 meter and the length of which exceeds 3 meters. However, the apparatus in accordance with the invention may also be used for the rolls of rolling mills which are less heavy.

The present invention is characterized in that the inductor is made of two end frames and of two lateral conductors interconnecting the two end frames so as to form an inductor having two longitudinal symmetry planes which are perpendicular with respect to each other, and in that a regulating device is provided for regulating the position of the device permitting to rotate the roll around its axis, such regulating device being arranged in such a manner as to permit the axis of the roll to coincide with the line intersecting the two longitudinal symmetry planes.

Since the rolls of a rolling mill wear out and must be turned and rehardened, the apparatus in accordance with the invention may be equipped with devices permitting to adapt itself to rolls of different diameters. In this respect, the lateral conductors have their ends bent at 90° and are at least temporarily mobile with respect to the end frames and connected to such end frames by their ends bent at 90°.

The invention will now be disclosed with reference to a preferred embodiment thereof illustrated in the accompanying drawings in which:

FIG. 1 illustrates a perspective view, partially in section, of an apparatus in accordance with the invention; and

FIG. 2 illustrates a perspective schematic view of the inductor in accordance with the invention.

Referring to FIG. 1, there is shown a base 1 anchored in the ground. On base 1 slide supporting structures 2, 3 and 4. Each supporting structure is independent from the others but the supporting structures 2, 3 and 4 each consist of a pair of structures one unit of each pair being illustrated in the drawings.

The two supporting structures 2, only one of which is shown, each support a portion of a device permitting to rotate a roll around its axis. Such device consists of two levers 6 equipped with motorized rollers 7. The position of levers 6 may be regulated by means of an appropriate control system which is illustrated schematically by a handle 8 and a threaded shaft 9. To facilitate the transmission of the driving power to the rollers 7, the levers 6 pivot around a rotary shaft 10 driving the

rollers 7 by means of chains 11 only one of which is shown. The shaft 10 is driven by a chain 12 operated by a motor 13. This arrangement may be identical at both ends of the roll of the rolling mill, but it is also possible to provide only one motor 13 at one end of the rolling mill.

The supporting structure 2 may also include a pneumatic tailstock 14 to ensure perfect centering of the roll 5.

10 The position of the supporting structure 2 with respect to roll 5 may be controlled by means of an appropriate control system illustrated in the drawings by a handle 15 and a threaded shaft 16.

Around the roll of the rolling mill 5 is placed a heating inductor including two end frames and two longitudinal conductors. This inductor is illustrated schematically in FIG. 2. The end frames are identified by reference numeral 17 and the lateral conductors by reference numeral 18. The inductor illustrated in FIG. 2 has two longitudinal symmetry planes, a vertical plane 19 and a horizontal plane 20. In addition, there is illustrated a vertical transversal symmetry plane 21. The three planes, 19, 20 and 21 are perpendicular with respect to each other. The lateral conductors 18 have ends 22 bent at 90° and the contact between these lateral conductors 18 and the end frames 17 is made at such bent ends.

In a practical embodiment of the invention, as illustrated in FIG. 1, the end frame consists of a sheet of conductors 23 bent in a U shape to constitute a plane structure the larger surface of which is perpendicular to the axis of the roll 5. This sheet of conductors 23 is connected by a mobile transverse member 24 which closes the U shape arrangement to form a square or a rectangle. The sheet of conductors 23 rests on a base 25 secured to the mobile supporting structure 3. At its upper portion, the sheet of conductors 23 is maintained by pneumatic clamps 26 permitting to tighten one against the other the transverse member 24 and the sheet of conductors 23. The transverse member 24 may pivot around an axis 28 secured to an upright member 29. The pivotal movement of transverse member 24 is controlled by a pneumatic motor, not illustrated in the drawing, acting on a lever 30. During the heating of the roll, the transverse member 24 joins the two extremities of the sheet of conductors 23 owing to the tightening exerted by the pneumatic clamps 26.

The lateral conductors of the inductor consist of sheets of conductors 31 having bent ends 32 ensuring the contact with the sheet of conductors 23. The tightening of the bent ends 32 against the conductors 23 may also be done by means of pneumatic clamps such as clamps 26 or by means of screws or other devices. The lateral conductors 31 may be subjected to considerable forces because of the magnitude of the current which flows through them. Because of that, the conductors 31 are held by an insulating concrete slabs 33 fixed to upright members 34 strengthened by brace members 35 secured to mobile supporting structures 4. The mobile supporting structures 4 may be moved perpendicularly to the longitudinal axis of the apparatus through a device regulating the position thereof which is not illustrated. Such a device may be a handle in a very simple case. It is important to ensure that the positioning of the mobile supporting structure 4 be done without hindering the symmetry of the inductor. Such symmetry does not need to be absolutely perfect

but departures therefrom are not tolerated at the locations where the larger forces are generated, hence along conductors 31.

The conductors 23 and 31 are arranged so that water is fed through them by means of connections 36. The pneumatic clamps 26 and the pneumatic tailstock 14 are connected to compressed air conduits, not illustrated, by means of connections 37.

To compensate for the heat losses through the ends of roll 5, the conductors 31 may be surrounded by magnetic field concentrators 38 made of laminated iron and disposed adjacent to the ends of roll 5.

An alternating current generator 39, illustrated in FIG. 2 only, may be placed on one of the mobile supporting structure 4, or each mobile supporting structure 4 may support a current generator suitably arranged for a series connection.

The apparatus in accordance with the invention operates as follows:

When a roll of a rolling mill is brought towards the apparatus by means of a rolling bridge, not illustrated, the transverse members 24 are pivoted around their axis 28 under the action of levers 30 and are thus placed in the vertical position. The roll is placed on rollers 7 and the levers 6 are regulated until the axis of the roll 5 coincides with the line intersecting the longitudinal symmetry planes 19 and 20 (FIG. 2) of the inductor. Subsequently, the supporting structures 4 are regulated so as to obtain a predetermined inductive coupling with the surface of the roll. Finally, the roll is rotated and the heating current is permitted to flow. The apparatus may be also equipped with means for hardening the rolls, not illustrated, and with other auxiliary devices. The regulation of the position may be done by means of servo-motors and of automatic measuring and controlling devices.

1. An induction heating apparatus used for the heating in depth of the surface of the rolls of a rolling mill comprising an inductor fed by an alternating current of low or medium frequency and including two end

5 frames and two lateral conductors interconnecting said end frames so as to form an inductor having two longitudinal symmetry planes which are perpendicular with respect to each other, a device for rotating a roll around its axis and means for positioning said roll rotating device in such a way that the axis of the roll is brought in line with the line intersecting the two longitudinal symmetry planes.

10 2. Apparatus as defined in claim 1, wherein said lateral conductors are bent at 90°, are at least temporarily mobile with respect to the end frames, and are connected to said end frames by their ends bent at 90°.

15 3. An apparatus as defined in claim 2, wherein the end frames comprise a U-shaped branch and a transverse member which is temporarily mobile so as to close or open the end frame.

4. Apparatus as defined in claim 2, wherein pneumatic clamps ensure positive contact pressure between the temporarily mobile lateral conductors and the end frames.

5. An apparatus as defined in claim 3, wherein pneumatic clamps ensure positive contact pressure between the temporarily mobile transverse members and the end frames.

20 6. An apparatus as defined in claim 1, wherein the device for rotating the roll around its axis is mounted on two first supporting structures which are movable longitudinally, wherein said end frames are mounted on two second supporting structures which are also movable longitudinally, and wherein the lateral conductors are mounted on two third supporting structures movable transversely with respect to the axis of the roll.

30 7. An apparatus as defined in claim 1, wherein levers supporting motorized rollers are provided and constitute the device for rotating the roll around its axis and wherein said levers and a device controlling the position of said levers constitute the means for positioning said roll rotating device.
